W. E. ARMISTEAD.
APPARATUS FOR MANUFACTURING ICE.
APPLICATION FILED AUG. 23, 1911.

1,062,530.

Patented May 20, 1913.

UNITED STATES PATENT OFFICE.

WILLIAM E. ARMISTEAD, OF SANDERSVILLE, GEORGIA.

APPARATUS FOR MANUFACTURING ICE.

1,062,530.

Specification of Letters Patent.

Patented May 20, 1913.

Application filed August 23, 1911. Serial No. 645,517.

To all whom it may concern:

Be it known that I, WILLIAM E. ARMISTEAD, a citizen of the United States, residing at Sandersville, in the county of Washington and State of Georgia, have invented 5 certain new and useful Improvements in Apparatus for Manufacturing Ice; and I do hereby declare the following to be a full, clear, and exact description of the invention, 10 such as will enable others skilled in the art to which it appertains to make and use the same.

This invention relates to improvements in an apparatus for making clear and pure ice 15 from raw water, and the present invention is directed especially to improvements in the construction disclosed by my pending application Serial No. 578,323, filed August 22, 1910, but is also applicable to other forms 20 of ice making apparatus.

The principal object of the invention is to provide means for insulating the inlet and outlet nozzles leading the water to and drawing it from the ice forming cans to 25 prevent freezing of the water in the nozzles.

Another object of the invention is to provide means for causing an even flow of the 30 brine around the ice forming cans from top to bottom thereof.

With the above and other objects in view the invention consists in certain combinations and arrangements of the parts herein-after described, and the novel features 35 thereof will be particularly pointed out in the appended claims.

For a clear understanding of the invention, reference will be had to the accompanying drawings illustrating a preferred embodiment thereof, and in the drawing like characters of reference indicate corresponding parts.

Figure 1 is a longitudinal section through the brine tank, the rest of the apparatus being shown in elevation; Fig. 2 is a detail sectional view on an enlarged scale of the ball and socket connection; and Fig. 3 is a similar view of the outlet or suction nozzle.

In the drawings 1 represents a brine tank provided at one end with a brine supply pipe 2 entering near the top and terminating in a downwardly turned vertical portion 3 having an open lower end 4 and also a plurality of apertures 5 through its sides. Entering near the bottom at the other end of the brine tank is an outlet pipe 6 having

an upwardly extending portion 7 open at its top end 8 and provided with perforations 9. By arranging the inlet and outlet pipes 3 and 7 in a vertical position at opposite ends of the brine tank and providing the sides of the pipes with perforations, an even flow and distribution of the brine around the ice forming cans from top to bottom thereof is obtained. The inlet and outlet pipes are connected in the usual manner to a brine circulating pump and brine cooler, neither of which is shown. Extending from the outlet pipe 6 is a pipe 6^a leading to a storage tank not shown. The 70 pipe 6^a is provided with a shut off valve 6^b, and when it is desired to withdraw the brine from the tank the valve is opened and the brine permitted to flow to the storage tank.

Arranged in spaced relation to the bottom 75 of the brine tank is a layer of insulating material 10, and below said insulating material is disposed a pipe 11 which extends from one end of the brine tank as at 12. The insulating material 10 is apertured as 80 at 12^a for receiving the vertical nipples 13 of the T fittings 14 and the end elbow 15 of the pipe 11. Each nipple 13, Fig. 2, has threaded therein a ball member 16 adapted to form a tight joint by contact with a 85 member 17 having a semi-cylindrical socket 18. The socket member 17 is provided with a flange 19 which is secured by bolts or rivets 20 or other suitable means to the bottom of each ice forming can 21.

In order to prevent the water passing through the ball and socket members from freezing therein insulation means as follows is provided:—The ball members 16 are made hollow for their entire length and 95 provided with insulation 21^a preferably a block of wood having an opening 22 therethrough. The center of the socket members 17 are also hollowed out from their semi-cylindrical sockets 18 for the rest of 100 their length and the bottoms of the ice forming cans 20 are provided with alining openings 23. Insulation 24 similar to that described is inserted in the hollowed out portions of the socket members 17 and 105 openings 23 preferably flush with the inside of the bottoms of the ice forming cans and same is provided with apertures 25. A space 26 is left between the insulating material 21^a and 24 to allow for the proper 110 seating of and clearance between the ball members 17 in the semi-cylindrical sockets

18. The ball members 16 of the couplings should project a sufficient height above the bottom of the brine tank, to permit them to project well above the surface of any brine that may remain in said tank after the brine has been drawn off. The ice forming cans 21 have their tops in alignment with the upper edges of the brine tank and are separated from each other by divisional plates 27 forming compartments 28 between which circulation is established by means of a vertical row of apertures 29 in the divisional plates.

A cover for the brine tank is designated 30 and is adapted to rest on the top edges of the ice forming cans for locking same in position. Arranged above the cover is a pipe 31 similar to the pipe 11 having the same kind of T fittings 32 and end elbow 20 fitting 33, the downwardly extending nipples 34 of which project through apertures 35 arranged above each ice forming can in the cover. Short pieces of pipe or nozzles 36 depend from the nipples 34 and their open ends extend a little below the top edges of the ice forming cans 21. The nozzles 36 are insulated and prevented from freezing shut by the water in the ice freezing cans by fitting inside each nozzle a block of wood 37, Fig. 3, or other suitable insulating material which is provided with an aperture 38. The apertures 38 are in vertical alignment with the apertures 25 through the bottom of the ice forming cans for permitting the circulation of the water therein.

The extending end 12 of the pipe 11 is provided with a T fitting 39 from which projects a vertical pipe 40 carrying at its upper end a filter 41 having its top edge substantially in alignment with the upper edges of the ice forming cans to maintain the proper water-level in the cans. The pipe 12 is connected with a source of water supply for filling the ice forming cans, and said pipe is provided with a shut-off valve 42. When the cans are filled the valve 42 is closed and the water caused to flow upwardly through the center of the ice forming cans by means of a circulating pump 43 connected by a flexible connection and the pipe 44 to the pipe 31; and from said pump extends a pipe 45 terminating in a suitable discharge connection into the filter 46.

From the foregoing it is apparent that the brine will flow evenly from top to bottom around the ice forming cans thus providing an equal amount of freezing and the different cans will be completely frozen and ready for harvesting at the same time; and then the brine may be readily withdrawn from the tank. At that time the members 16 of the coupling will project up above the surface of the insulating bottom of the tank, and any brine adhering to said bottom can-

not reach the openings in said members, thus preventing any of the brine from finding its way into the pipe 11, and contaminating the raw water. As the inlet and outlet nozzles are insulated the freezing of the water therein is prevented.

It is to be understood that slight changes in the details of construction and the arrangement of the parts may be resorted to without sacrificing any of the advantages or departing from the spirit of the invention.

Having fully described my invention, what I claim is:

1. In an ice making apparatus, the combination of a brine tank, an inlet and an outlet pipe for the brine tank, ice forming cans arranged in the tank, extensions of said pipes arranged vertically at the opposite ends of the tank, the extensions being perforated through their sides to cause an even flow of brine around the cans from their tops to bottoms, and a pipe fitted with a shut-off valve for permitting the withdrawal of the brine from the tank, substantially as described.

2. In an ice making apparatus, the combination of a brine tank provided with a plurality of transverse division plates each having a vertical series of apertures therein, ice forming cans in the compartments formed by the division plates, an inlet pipe entering near the top of one of the end compartments and an outlet pipe projecting from the other end compartment near the bottom thereof, an extension of the inlet pipe turning downwardly and provided with apertures through its sides, an extension of the outlet pipe turning upwardly and having its sides perforated, and a pipe extending from the outlet pipe for withdrawing the brine from the tank, substantially as described.

3. In an ice making apparatus, the combination of a brine tank provided with a plurality of transverse division plates each having a series of apertures therein, ice forming cans in the compartments formed by the division plates, a water pipe disposed below said cans, the bottoms of the cans being removably connected with the water pipe, a second water pipe above and communicating with the upper portions of said cans, a filter in alignment with the upper edges of said cans and connected to the first water pipe, a circulating pump connected with the second mentioned water pipe, and a conduit extending from the circulating pump to said filter, substantially as described.

4. An ice making apparatus, comprising a brine vat, a can mounted in said vat, a water supply pipe having a nozzle projecting up above the bottom of said vat, said nozzle being provided with a perforated lining of insulating material, and terminat-

ing in a hemispherical portion, and a short pipe connected to the bottom of said can, and provided with a socket to receive said hemispherical portion of the nozzle, the two forming a ball and socket joint supporting said can, with a perforated insulating lining for said short pipe, forming with said nozzle a continuous insulating passage for the inflow of water into the can, with means for supplying the brine to and drawing off the brine from said vat, substantially as described.

5. An ice making apparatus, comprising a brine vat having a raised, insulating false bottom, a can mounted in said vat, a water supply pipe having a nozzle projecting up above the insulating bottom of said vat, said nozzle being provided with a perforated lining of insulating material, and terminating in a hemispherical portion, and a short pipe connected to the bottom of said can, and provided with a socket to receive said hemispherical portion of the nozzle, the two forming a ball and socket joint supporting said can, with a perforated insulating lining for said short pipe, forming with said nozzle a continuous insulating passage for the inflow of water into the can, with means for supplying the brine to and drawing off the brine from said vat, substantially as described.

6. An ice making apparatus, comprising a brine vat, a can mounted in said vat, a water supply pipe having a nozzle projecting up above the bottom of said vat, said nozzle being provided with a perforated lining of insulating material, and terminating in a hemispherical portion, and a short pipe connected to the bottom of said can, and provided with a socket to receive said hemispherical portion of the nozzle, the two forming a ball and socket joint supporting said can, with a perforated insulating lining for said short pipe, forming with said nozzle a continuous insulating passage for the inflow of water into the can, and a water outlet pipe projecting down into the center of the top of said can for drawing off the water from said can, said outlet pipe being provided with a perforated insulating lining, with means for supplying the brine to and drawing off the brine from said vat, substantially as described.

7. An ice making apparatus, comprising a brine vat having a raised, insulating false bottom, a can mounted in said vat, a water supply pipe having a nozzle projecting up above the insulating bottom of said vat, said nozzle being provided with a perforated lining of insulating material, and terminating in a hemispherical portion, and a

short pipe connected to the bottom of said can, and provided with a socket to receive said hemispherical portion of the nozzle, the two forming a ball and socket joint, with a perforated insulating lining for said short pipe, forming with said nozzle a continuous insulating passage for the inflow of water into the can, and a water outlet pipe projecting down into the center of the top of said can for drawing off the water from said can, said outlet pipe being provided with a perforated insulating lining, with means for supplying the brine to and drawing off the brine from said vat, substantially as described.

8. An ice making apparatus, comprising a brine vat, a can mounted in said vat, a water supply pipe having a nozzle projecting up above the bottom of said vat, said nozzle being provided with a perforated plug of wood forming an insulating lining therefor, and terminating in a hemispherical portion, and a short pipe connected to the bottom of said can, and provided with a socket to receive said hemispherical portion of the nozzle, the two forming a ball and socket joint to support said can, the said short pipe being provided with an insulating lining consisting of a perforated plug of wood, said short pipe forming with said nozzle a continuous insulating passage for the inflow of water into the can, with means for supplying the brine to and drawing off the brine from said vat, substantially as described.

9. An ice making apparatus, comprising a brine vat having a raised, insulating false bottom, a can mounted in said vat, a water supply pipe having a nozzle projecting up above the insulating bottom of said vat, said nozzle being provided with a perforated plug of wood forming an insulating lining therefor, and terminating in a hemispherical portion, and a short pipe connected to the bottom of said can, and provided with a socket to receive said hemispherical portion of the nozzle, the two forming a ball and socket joint to support said can, with a perforated plug of wood in said short pipe forming an insulating lining, thus forming with said nozzle a continuous insulating passage for the inflow of water into the can, with means for supplying the brine to and drawing off the brine from said vat, substantially as described.

In testimony whereof, I affix my signature, in presence of two witnesses.
